UNITED STATES PATENT OFFICE.

THEODOR M. MUELLER, OF DETROIT, MICHIGAN.

ТИЛТИНГ ЛАМПА.

1,276,070.

Specification of Letters Patent. Patented Aug. 20, 1918.

Application filed June 15, 1917. Serial No. 174,851.

To all whom it may concern:

Be it known that I, THEODOR M. MUELLER, formerly a subject of the Emperor of Germany, now having first United States citizenship papers, residing at Detroit, in the county of Wayne and State of Michigan, have invented certain new and useful Improvements in Tilting Lamps, of which the following is a specification, reference being 10 had therein to the accompanying drawings.

The invention relates to lamps designed for use as headlights upon vehicles and has particular reference to the construction of means for tilting the lamp. In the present state of the art there have been devised various constructions of tilting lamps with which the operator can turn the light downward when passing other vehicles, thereby avoiding a blinding glare. Where mechanical connections are used for accomplishing this adjustment these are necessarily complicated to avoid interference with other mechanism upon the car and every working joint introduced into the connection is a 25 source of possible trouble. It is therefore the primary object of my invention to obtain a construction in which all working joints other than the pivots on which the lamp tilts are dispensed with. A further object is to obtain a construction of electromagnetic operating mechanism which is applicable to standard constructions of lamps without change therein. Still another object is to combine the tilting with a dimming 35 of the lamp and still further to utilize the energy abstracted from the lamp in the dimming of the same in whole or in part for the tilting operation.

In the drawings:

40 Figure 1 is a vertical central section through a lamp to which my improvement is applied;

Figs. 2 and 3 are respectively rear and side elevations of the lamp reflector with the attached parts of the tilting mechanism;

45 Figs. 4 to 6 are diagrams illustrating the electric circuits.

A is the casing of a lamp, B is the reflector therein, C the lamp bulb and D the lamp socket, therefor,—all of usual construction. To tilt the lamp to direct the rays downward the reflector B is mounted upon pivots within the casing A and is actuated magnetically by the following construction. E 50 is an annular flange preferably formed integral with the flange of the lamp socket D,

which latter as well as the reflector B is usually formed of non-magnetic material. F and F' are segments of magnetic metal which are secured to the flange E on 60 diametrically opposite sides thereof and which are arranged eccentric to the axis of the lamp and concentric with the axis of the pivots G. H is a capped-shaped member formed of magnetic metal which surrounds 65 the lamp socket D with sufficient clearance to permit of the tilting of the same, being centrally secured to the casing A by suitable means, such as the headed bolt I and nut J. K is a second capped-shaped member formed 70 of magnetic metal having a portion K' sleeved upon and secured to the member H and also having a portion K² which is expanded in diameter to be spaced from the member H concentric thereto. L is a magnet 75 coil arranged in the space intermediate the member H and the expanded portion K² of the member K. M and N are flanges on the inner ends of the members H and K and which are arranged concentric to the 80 axis of the pivots G.

With the construction as described the members H and K together with the coil L form in effect an electromagnet with concentric annular pole-pieces formed by the 85 flanges M and N. These flanges are so arranged as to be in close proximity to the segmental flanges F and F' secured to the tilting reflector B, and the arrangement is also such that when the magnet is energized 90 the segments F and F' will be drawn to bridge the magnetic gap between said pole-pieces, thereby tilting the reflector B upon the pivots G. In normal condition when the magnet is deenergized, a spring O extending between hooks P and Q on the member K and reflector B will hold the latter in its normal position for directing the rays concentric to the axis of the lamp, and a stop R of non-magnetic metal secured to 95 the flange N and engaging the segment F' will hold the reflector from further tilting.

The electrical connections to the lamp and its operating magnet may be as shown in Figs. 4, 5 and 6, in which S is the battery 105 and T the controlling switch. In Fig. 4 in one position T' of the switch the magnets L are arranged in series with the filaments of the lamp C, while in another position T² the magnets are shunted out and the lamps 110 alone are in circuit. In Fig. 5 the magnets L and lamps C are in multiple or parallel

- and may be independently controlled by switch blades U and U'. In Fig. 6 a compound construction is shown, the magnet being provided with two coils L' and L², the former being in series with the lamp C and the latter in parallel therewith. With each of these constructions the lamp may be tilted by adjusting the switch T, but in the construction shown in Fig. 5 this is accomplished without any dimming action in the lamps, while in the constructions shown in Figs. 4 and 6 the lamps are dimmed. The energy required for tilting is very slight and consequently by properly proportioning the coils in the construction shown in Fig. 6 the same amount of energy may be used when the lamps are tilted as is consumed for the full illumination of the lamps when stationary.
- 20 The construction described can be manufactured at low cost as the several elements of the magnet and armature may be formed of stamped or pressed sheet-metal. The assembly of the structure is also simple and 25 the member K in addition to its magnetic function may serve for the mounting of the pivot bearing V in which the pivots G are secured. The parts of the magnet may be assembled outside of the case and then secured by the single bolt I, while the armature segments F and F' being attached to the reflector are brought into the proper relation with the magnet by engagement of the pivots G with the bearings V. The electrical connections for both the lamp and the magnet are formed by flexible conductors W and W' which engage a connector plug X in the casing A.
- In operation whenever it is desired to tilt 40 the lamp, by adjusting the switch T from the position T² to the position T' the magnet will be energized, causing the armature segments F and F' to move across the gap in the magnetic circuit between the pole-pieces 45 M and N. These armature segments as well as the pole-pieces M and N being spherical segments in eccentric relation to each other, it is obvious that the magnetic action is progressive, beginning at the point of slightest 50 gap and continuing until the segments are concentric. This arrangement cuts down upon the amount of energy required to overcome the inertia of the parts and consequently the current consumed.
- 55 It will be noted that there are no working joints in the mechanism other than the turning of the pivots in the bearings V so that there are no parts to wear or to rattle.
- What I claim as my invention is:
- 60 1. In a lamp, the combination with an outer casing, of a reflector pivotally mounted therein, a lamp socket mounted on said reflector, an annular electro-magnet surrounding said lamp socket with a clearance 65 for movement thereof and secured to said outer casing in the space between the same and the reflector, and an armature mounted on said reflector coöperating with said magnet when energized to cause the tilting of the reflector.
2. In a lamp, the combination with the outer casing and an inner reflector pivotally mounted therein, of a lamp socket mounted on said reflector and extending in the space between the same and said outer casing, an electro-magnet having annular poles surrounding and spaced from said lamp socket and mounted upon the outer casing and an armature mounted on said reflector coöperating with said magnet to effect the tilting of the reflector.
3. In a lamp, the combination of an outer casing of a reflector pivotally mounted therein, an electro-magnet in the space between said reflector and outer casing, and secured to the latter, said magnet having pole-pieces concentric with the axis of the pivot for the reflector, and an armature mounted on said reflector coöperating with said magnet to effect a tilting when the magnet is energized.
4. In a lamp, the combination with an outer casing and an inner reflector, of a lamp socket mounted on said reflector, an electro-magnet having annular pole-pieces surrounding and spaced from said lamp socket and also forming spherical segments, alined pivots upon said reflector concentric with said spherical segments, pivot-engaging bearings mounted upon the outer pole-piece of said magnet and means for mounting said magnet within said outer casing and in the space between the same and said reflector.
5. In a lamp, the combination with an outer casing and a reflector having pivot bearings, of an electro-magnet comprising two cupped members one sleeved upon the other and each having an annular flange, a magnetic coil between the inner and outer member, means for securing the inner member to said casing, pivotal bearings on the outer member engaging the pivots on said reflector, armature segments mounted on said reflector and adapted to bridge the gap between said annular flanges when the magnet is energized, and means for yieldably holding the armature in eccentric relation.
6. In a lamp, the combination with the outer casing, of a reflector pivotally mounted therein, an electro-magnet for tilting said reflector, an electric lamp, an electric circuit for said lamp, and means for connecting said magnet into said circuit to simultaneously dim the lamp and energize said magnet to tilt the reflector.
7. In a lamp, the combination with a casing, of a reflector pivotally mounted therein, an electro-magnet for tilting said reflector, an electric lamp, a circuit for said electric

lamp, and a coöperating electric circuit for said magnet, whereby said lamp may be dimmed and said magnet operated by the energy conserved in the dimming of the lamp.

8. In a lamp, the combination with an outer casing of a reflector pivotally mounted therein, an electro-magnet in the space between said reflector and outer casing, and

secured to the latter, said magnet having 10 spherical segmental pole-pieces, and an armature mounted on said reflector having spherical segments in eccentric relation to said pole-pieces and adapted to coöperate therewith to effect a tilting when the magnet 15 is energized.

In testimony whereof I affix my signature.
THEODOR M. MUELLER.
